METHOD AND DEVICE FOR THE MECHANICAL PRODUCTION OF MULTIPLE WALLED PAPER BAGS

Max Goder, Neuss-on-the-Rhine, Germany

Application January 6, 1937, Serial No. 119,351
In Germany January 10, 1936

9 Claims. (Cl. 93—18)

This invention relates to a method and a device for the mechanical production of multiple-walled paper bags with cross bottom or block bottoms with reinforced mouth in which the tube forming the bag is formed by approaching paper webs to be unwound from rolls, and has for its object the simplification and acceleration in the production of the above mentioned paper bags.

The main feature of the invention is, that the paper webs are unwound from rolls in a transverse direction to the side folds to be made for shaping the bag, and severed so that the severed sheets are fed to the subsequent operating stations with their side edges stepped in the direction of feed and this stepped position is preserved after the sheets have been superimposed. By this method of shaping the bag it is not only possible to obtain a quick continuous production, but to cause on the one hand the mouth edge of the shaped blank to lie in a direction which assists this continuous production and on the other hand a simplification for carrying out the method and at the same time to increase the output. After the paper webs have been superimposed the creasing for the side and bottom folds and the gumming of the side flaps take place followed by the folding and gumming of the side flaps, and the subsequent folding transversely to the direction of feed, sticking and tube formation, whereupon the portion of the tube necessary for forming the bottom is opened and brought into square shape, the gumming, folding and sticking of the cross bottom taking place continuously.

The sheet producing the wrapper is, according to the invention, besides being stepped with respect to the side edges of the two superimposed sheets whose side edges are stepped with respect to each other is also stepped with respect to the transverse edges of the sheets, so that a projecting edge strip is produced at one of the transverse edges which, after having been folded over, reinforces the mouth of the bag.

The reinforcement of the mouth can, according to the invention, also be effected by feeding to the superposed sheets a narrow edge strip to be also pulled off a roll and this strip is stuck onto the sheets. The edge strip projects slightly beyond the flush edge of the sheets, so that it can be folded over.

The printing of the roll often does not allow perfect and uniform application of printing ink during the printing of a whole roll owing to the lack of possibility of observation during the continuous uninterrupted feed. Periodical observa-

tion of the printing of the roll is certainly possible by repeatedly stopping the machine during the printing operation. This stopping of the machine, however, prolongs the working time and does not enable a continual observation of the print.

According to the invention, therefore, the application of the wrapping sheet can be carried out by feeding to the superimposed sheets which may be stepped at the side as well as at the transverse edges, as desired, a sheet serving as wrapper taken from a pile in the same direction of feed and by sticking this wrapper sheet on the superimposed sheets. The wrapper sheet is fed with the severed superimposed sheets in such a manner that, besides being stepped in the direction of feed i. e. at the side edges of the sheets, the front and rear i. e., transverse edges of the wrapper are stepped relatively to the corresponding edges of the webs pulled off the rolls.

Machines are known, in which the wrapper sheet is fed to a paper sheet severed from a web, or a wrapper from a pile is brought on to the superimposed sheets. These machines, however, do not allow the wrapper taken from the pile to be stepped both longitudinally and transversely. The superimposed sheets are conveyed in longitudinal direction through the machine so that the mouth of the bag leads. The wrapper sheet is fed at right angles to the direction in which the superimposed sheets are fed.

The sheets separated from the web are then placed on the wrapper and the wrapper part is folded over or pressed on by means of levers and rams. It is not possible to step the front edges of the paper layer fed from the web.

A machine for carrying out the method according to the invention comprises a sucker for taking the wrapper sheets from a pile and rollers which convey the wrapper sheets to stops against which the severed and superimposed sheets are also fed to unite with the wrapper sheets. At the joint where the superimposed and wrapper sheets are brought together a folding device is arranged for folding and pressing on the projecting parts of the wrapper sheet serving as reinforcement for the mouth.

For raising the end of the tube necessary for forming the bottom, a bottom lifter and a sucking cylinder gripping and lowering the front fold edge and a suction slide for lowering the rear bottom part are provided, which slide acts upon the said bottom part until it is formed into a square shape.

The tube end formed into a bottom is, accord-

ing to the invention, provided with a cover sheet.

An embodiment of the invention is illustrated by way of example, in the accompanying drawings in which:—

5 Fig. 1 shows in plan view a portion of the three webs from which the sheets to be superimposed and the wrapper sheet are severed, the severing means or blades being supposed to be so arranged that the side edges of the severed sheets are
10 stepped.

Fig. 2 shows the two superimposed sheets with their stepped side edges after they have been severed from the web to form a bag, the wrapper sheet stepped with respect to the stepped side edges and to the flush transverse edges of the two sheets.

Fig. 3 shows in dotted lines the folds for the sides and the bottom of the bag.

Fig. 4 shows the position of paste strips on the stepped side edges at one side of the sheets and the wrapper, and the folding of the side edges at the other side.

Fig. 5 shows the paper tube formed by the sheets and the wrapper.

25 Fig. 6 shows the position of paste strips on the bottom portion of the tube.

Fig. 7 shows the finished bag.

Fig. 8 shows the feeding of a narrow additional strip for reinforcing the bag mouth.

30 Fig. 9 shows in plan view the position of the narrow additional strip.

Fig. 10 shows a device for severing sheets from three webs.

35 Fig. 11 is a diagrammatic view of a machine in which the wrapper sheet is taken from a pile and, together with the two superimposed inner sheets, is folded into a bag.

Fig. 12 is a plan view of the device for feeding the wrapper to the superimposed sheets.

40 Figs. 13 and 14 show respectively, the wrapper sheet with its reinforcing strip ready for folding down, and after the strip has been folded down.

Figs. 15 to 17 are side elevations of the device for forming the tube in different positions.

45 Figs. 18 and 19 are side elevations of the device for forming the cross bottom.

Fig. 1 shows a web 1' from which the wrapper 1, Fig. 2, is severed, and two webs 2' and 3' from which the superimposed sheets 2 and 3 are severed, respectively. This can be done by a device as illustrated in Fig. 10 where staggered cylinders 33, 33', and 33'' are provided and equipped with blades 34, 34', and 34'', respectively, for severing sheets 1, 2, and 3 from the respective webs 1', 2', and 3' in stepped relation. The severed sheets are fed in such a manner that the paper sheets are stepped at their front and rear side edges, as shown in Fig. 2. The steps extend transversely to the direction of the feed which is supposed to be from the left to the right in Fig. 1, as indicated by the arrow, and also transversely to the side folds 8 and 9, (Fig. 3) to be carried out to form the bag. In Fig. 2, the transverse edges of the two superimposed sheets 2 and 3 are flush and only the wrapper sheet 1 is stepped to form a projecting strip 4 at one of the transverse edges but it is understood that the transverse edges of the sheets 2 and 3 may also be stepped, if desired. The length of the sheets 1, 2 and 3 is equal to the developed bag width. When the sheets 1, 2, 3 have been stuck together, the strip 4 of the sheet 1 destined to produce the reinforcement of the mouth, is folded over and pressed tightly on to the sticking stripe 5 by a suitable device after this

stripe has been applied. The creases 6 (Fig. 3) for the bottom folds and the creases 7, 8 (Fig. 3) for the side folds are then produced. Hereupon the front side fold 9 (Fig. 4) is formed and the stepped sheet ends 10, 11, 12 of the wrapper 1 and of the inner 2, 3 (Fig. 4) are gummed whereupon the second side fold is made and the tube formed, both the wrapper and also the inner sheets 1 and 2 being separately stuck on one another. The tube thus formed is then fed with the tube openings 14, 15 positioned transversely to the direction of feed, the tube part 16 (Fig. 5) necessary for the bottom being opened or formed into square shape (Fig. 6). Hereupon paste 17 is applied on the bottom (Fig. 6) to enable the bottom points 18, 19 (Fig. 7) to be folded over and stuck on one another.

According to Figs. 8 and 9 the reinforcement of the mouth is not effected by the wrapper. In this instance a narrow additional strip 20, which is 20 likewise pulled off a roll 20', is fed to the paper webs 1', 2', and 3' here arranged in opposite sequence to that shown in the other figures forming the inner sheets 2, 3 and the wrapper 1 and stuck onto the latter, so that a reinforcement of 25 the bag mouth is produced.

The reinforcing strip 4 is preferably cut according to Figs. 2 and 3 in such a manner that at the corresponding transverse edges of the sheets 2 and 3 the strip is set back from the stepped rear side edges whereas at the other side it projects beyond the stepped front edges.

In the machine for carrying out the invention illustrated in Figs. 11 to 19 the production takes place in the following manner:—

The paper webs 21 and 22 corresponding to the webs 2' and 3' of the previous figures are unwound from supply rolls and guided over rollers 23 and 24 respectively. The paper web 22 (Fig. 11) is provided with paste for example by means of the 40 pasting cylinder 25 which receives paste from the rollers 26 and 27 of the paste box 28. As counter bearing for the pasting cylinder a cylinder 29 is provided. The two paper webs 21 and 22 are then severed by devices such as 33' 34' and 33'', 34'' in 45 Fig. 10, and the severed sheets 2 and 3 enter between a pair of rollers 30 and 31 which deliver them to other pairs of feeding rollers 30', 31', and 30'', 31'', and finally the sheets are conducted against stops 37. During this operation sheet 1 50 is lifted by a sucker 40 off the pile 38 resting on a table 39. This table 39 can be raised by a pinion 41 cooperating with a rack 42 according to the thickness of the wrapper sheets. After the removal of the uppermost sheet of the pile by means of the sucker 40, this sucker moves into the position shown in dotted lines and conducts the sheet between the cylinders 43 and 44. A pasting roller 45 imparts a coat of paste to the cylinder 44 for the strip of paste 5 on the projecting strip 4 of the wrapper sheet 1 (Figs. 2 and 12) which serves for reinforcing the bag mouth, as described. The pasting roller takes its paste from the rollers 47 and 48 of the paste box 48. The wrapper is 60 then conducted by the rollers 49 and the endless bands 50 against the stops 51. When the two inner sheets 2 and 3 severed from the paper webs 21 and 22 and the wrapper sheet have been brought together in stepped relation, as described 70 with the wrapper sheet underneath, the strip 4 (Fig. 13) is folded over by means of folding flaps 52 (Fig. 12). These folding flaps are actuated by bevel gears 53. The inner and wrapper sheets (Fig. 14) are thus stuck together. These stuck 75

sheets are then gripped by the movable grippers 54 of the cylinder 55 and of the counter cylinder 56 and fed on. Sinkable folding blades 56' and 57 are arranged in the cylinder 55 and resilient 5 clamping and folding bars 59 and 60 in the cylinder 58. As soon as the paper sheets come between the cylinders 55 and 58 the unit will be pressed at a predetermined folding point into and held in the clamping and folding bar 59 by the 10 folding blade 57 (Fig. 15) so that the now raised sheet portion 61 (Fig. 15) is folded over when passing the folding cylinder 62. This makes the first side fold 8. The portion of the sheet destined to receive the second fold 9 is then pressed into 15 and held in the clamping and folding bar 60 by the folding blade 59'. The first folding bar 59 then liberates the unit as soon as it has arrived under the cylinder 63 (Fig. 16). The forward portion 64 of the unit slides over the guide bars 65 20 whereas the rear sheet portion which is still between the cylinders 63 and 58 is provided with paste by the pasting roller 66 which receives its paste from the paste box 69 through the intermediary of rollers 67 and 68. The rear portion of 25 the sheet is held by the clamping and folding bars 60 until the paper, changing its direction of movement, is formed into a tube, that is in forming the second fold between the cylinders 58 and 70 (Fig. 30 11) the direction of movement changes in so far that the front folded edge now becomes the rear folded edge. The tube, after being shaped and stuck by the cylinders 58 and 70 (Fig. 11), passes over the guides 71 between the rollers 72, 73, 74, 75. In passing through these rollers the creases 35 for the bottom square are produced by the creasing blades 76. The tube then passes between the rollers 77, 78, 79 and 80 and the tube end in which the bottom forming has to take place is raised by the bottom lifter 81 of the roller 80 in such a 40 manner that it stands at right angles to the surface of the tube. The front fold edge b of the tube end c moving ahead slides into the angle guide piece 82 (Fig. 18) against the suction cylinder 83 by which it is sucked on through the suction holes 84 and, during the rotation of the cylinder 83, is held by this cylinder, laid down and 45 formed to square shape. The portion which is not gripped by the cylinder 83 is gripped by the suction slide 85 and laid down in the following manner. As soon as the front fold edge b of the tube end c is gripped by the suction holes 84 of the cylinder 83 the suction slide movable towards the point of contact between the cylinders 83 and 86, 50 jumps forward, grips the rear fold edge 87 of the tube edge c and presses it down. The suction slide 85 (Fig. 19) subsequently remains in its lowered position until the incision d has arrived under the cylinder 83 under which the bottom square is folded. The workpiece then travels between the cylinders 88, 89, 90, 91, 92 and 93, the bottom points of the bottom shaped to a square bag provided with paste by the roller 94 to which 55 paste is fed from the paste box 97 by the rollers 95 and 96. When passing between the cylinders 98, 99 and 100 and 101 the two bottom points are folded over by the folding blades 102 and stuck the one on the other. After the bottom bag has been 60 thus far finished a cover sheet is stuck on to the cross bottom. The sucker 103 takes a cover sheet from the pile 104 and moves in to the position shown in dotted lines. The individual sheets are here sucked by suction air by the suction holes 105 of the cylinder 106 and released by the sucker 103. 65 During the rotation of the cylinder 106 the sur-

face of the sheet is pasted by the pasting roller 107 to which the paste is supplied from the paste box 110 by the rollers 108 and 109. The work piece on coming out from between the cylinders 100 and 101 encounters the cover sheet held and pasted by 5 the cylinder 106 so that the two parts (cover sheet and cross bottom) are stuck together between the rollers 106 and 111, the suction holes 105 release the cover sheet. The finished article is conveyed by the rollers 106 and 111 over the guides 112 10 between the bands 113 and 114 which are wound around rollers 115, 116 and 117, 118. The work pieces are again pressed by these bands to improve the sticking and then collect in a pile 120 on the table 119. 15

I claim:

1. A machine for mechanically producing multiple walled paper bags with cross or block bottoms, comprising in combination a sucker adapted to remove a wrapper sheet from a pile, rollers adapted to receive said wrapper sheet from said sucker, stops adapted to arrest the movement of said sheet, means for feeding a plurality of superposed webs, means for cutting said webs into sheets, means for guiding said sheets against said stops on the top of said wrapper sheet, and means for uniting said blanks with said wrapper sheet. 20

2. In a machine as specified in claim 1, a folding device at the point where said sheets and said wrapper are united, adapted to fold over and press a projecting portion of said wrapper sheet 30 to form a reinforcement of the bag mouth.

3. In a machine as specified in claim 1, means for forming sheets and said wrapper sheet into a tube, a bottom lifter adapted to raise one end of said tube to form a bottom, a suction cylinder adapted to grip and press down the front folded edge of said tube, and a suction slide adapted to press down the rear edge of the bottom part of 35 said tube and to form said bottom into square 40 shape.

4. In a machine as specified in claim 1, means for forming sheets and said wrapper sheet into a tube, a bottom lifter adapted to raise one end of said tube to form a bottom, a suction cylinder 45 adapted to grip and press down the front folded edge of said tube, and a suction slide adapted to press down the rear edge of the bottom part of 50 said tube and to form said bottom into square shape, and means for applying a cover sheet onto the tube end shaped to form the bag bottom.

5. A method for mechanically making multi-wall paper bags with cross bottoms, consisting in feeding webs of paper in a direction transverse to the position of the side folds in the bags, severing the webs into sheets in such manner that the side edges of the severed sheets are stepped, superimposing and feeding the sheets to the subsequent operating stations at the same time preserving their stepped relation, in feeding a strip, together with the said webs, and pasting the strip to one of the superimposed sheets at that transverse edge which corresponds to the mouth of the bag. 60

6. A method for mechanically making multi-wall paper bags with cross bottoms, consisting in feeding webs of paper in a direction transverse to the position of the side folds in the bags, severing the webs into sheets in such manner that the side edges of the severed sheets are stepped, superimposing and feeding the sheets to the subsequent operating stations at the same time preserving their stepped relation, in feeding a strip, together with the said webs, in such position with 70 75

respect to the superimposed sheets that it projects from that edge of the superimposed sheets which corresponds to the mouth of the bag, pasting the strip to one of the superimposed sheets, 5 folding the strip down onto the sheets, and pasting its folded-down portion to the other sheet.

7. A method for mechanically making multi-wall paper bags with cross bottoms, consisting in feeding webs of paper in a direction transverse 10 to the position of the side folds in the bags, severing the webs into sheets in such manner that the side edges of the severed sheets are stepped, superimposing and feeding the sheets to the subsequent operating stations at the same time preserving their stepped relation, in feeding a strip, 15 together with the said webs, in such position that at one end it projects beyond, and the other end is set back from, the corresponding side edge of the superimposed sheets at that transverse edge 20 which corresponds to the mouth of the bag, and pasting the strip to the edge.

8. A method for mechanically making multi-wall paper bags with cross-bottoms, consisting in feeding webs of paper in a direction transverse 25 to the position of the side folds in the bags, severing the webs into sheets in such manner

that the side edges of the severed sheets are stepped, superimposing and feeding the sheets to the subsequent operating stations at the same time preserving their stepped relation, in stepping the sheets also at their transverse edges, 5 feeding a wrapper sheet from a pile in the same direction in which the superimposed sheets are fed, and pasting the wrapper sheet to the superimposed sheets.

9. A method for mechanically making multi-wall paper bags with cross bottoms, consisting in feeding webs of paper in a direction transverse to the position of the side folds in the bags, severing the webs into sheets in such manner that the side edges of the severed sheets are stepped, 10 superimposing and feeding the sheets to the subsequent operating stations at the same time preserving their stepped relation, in stepping the sheets also at their transverse edges, feeding a wrapper sheet from a pile in the same direction 15 in which the superimposed sheets are fed, stepping the wrapper sheet with respect to the superimposed sheets at the side and at the transverse edges, and pasting the stepped wrapper sheet to the superimposed sheets. 20

MAX GODER. 25
